UNITED STATES PATENT OFFICE

WALTER JOHN BROWN, OF BROOKLANDS, ENGLAND, ASSIGNOR TO ASSOCIATED ELECTRICAL INDUSTRIES LIMITED, OF LONDON, ENGLAND, A CORPORATION OF ENGLAND

ELECTRICAL AMPLIFYING SYSTEM

Application filed August 9, 1927, Serial No. 211,658, and in Great Britain September 10, 1926.

My invention relates to electrical amplifying systems, and particularly to systems of the type in which a plurality of thermionic valves are utilized for different types of amplification, as, for example, radio receiving systems in which certain valves amplify the voltage of the signal at high frequencies, and other valves supply relatively heavy currents to a sound reproducing device such as a loud speaker.

A system of the kind referred to usually comprises a plurality of amplifying stages that require only a small amount of anode supply current, and an output, or power, stage employing a valve or valves in which the voltage amplification is usually low but the anode current consumption is high.

Since the amplification of the output or power stage is low, a small amount of deviation from true constancy of voltage of its anode supply does not produce any appreciable effect in a loud speaking telephone and, consequently, the current for this stage may be supplied through a filter of large current capacity, but of relatively low attenuation.

The earlier amplifying valves, such as those used for high frequency amplification and for demodulation, on the other hand, owing to the fact that there may be a very large degree of amplification between them and the power stage, must be supplied with anode current at a voltage which differs from a constant voltage by only very minute variations. In other words, the amplifying stages, particularly those early in sequence, must be supplied through a filter of very great attenuation, although its current capacity may be relatively small. The mechanical dimensions and weight of an electrical filter increase with its current capacity and also with the degree of attenuation required. Consequently a single filter to deliver the current required for the output stage, while at the same time having the degree of attenuation required in order that it may deliver current to the preceding stages without causing undesirable noise or hum in the loud speaker, is a somewhat large, heavy and expensive apparatus.

It is accordingly an object of my invention to provide means for economically supplying

power to the various thermionic valves comprised in an amplifying system.

My invention also includes the combination of two electrical low-pass filters, one having a high attenuation and low current carrying capacity, and the other having low attenuation and high current carrying capacity.

In amplifying instruments employing my invention the risk of retroactive coupling between the last stage of amplification and one or more stages earlier in sequence, by an impedance common to both stages, is also minimized.

Accordingly to my invention, in a wireless or like amplifying instrument employing a plurality of thermionic valves for supplying audio frequency current to the loud speaker, the last or power stage of amplification requiring a large anode current is fed through a filter having a relatively low attenuation and a relatively high current capacity, and another stage or stages earlier in sequence and requiring relatively small anode current is or are fed from another filter of high attenuation and low current capacity.

In carrying out my invention as applied to a wireless receiving instrument, consisting of a detector valve, resistance or transformer coupled to two voltage amplifying valves, which amplifying valve may also be resistance or transformer-coupled to one another, and a power valve which is resistance or transformer-coupled to the last one of the voltage amplifying valves, the last or power valve may be supplied with anode current from a filter of a single stage comprising a capacitor in shunt and a choke coil in series.

The detector and voltage amplifying apparatus may all be fed from a common filter of 2, 3, or 4 stages, each consisting of capacity in parallel and inductance in series.

In a receiver of the kind described great sensitivity and economy in anode current is obtained by employing valves having a high voltage amplification factor, say about 30 or 40, in the first three positions, and by employing high values of resistance of the order of half a megohm in the anode circuits. On the other hand it is customary to employ in the last or output stage a valve having a

low voltage amplification factor, say between 3 and 6, and a correspondingly high anode current, in order to deliver sufficient power to the loud speaker without distortion.

In such an instrument, the current required by the last or power valve may be of the order of 25 milliamperes. On the other hand the current required by the detector and amplifying valves rarely exceeds a quarter of a milliampere per valve. Thus the total current taken by the detector and two voltage amplifying valves may very probably not exceed three quarters of a milliampere. Consequently, the filter apparatus for supplying these three valves may be made quite small, notwithstanding the high degree of attenuation which is necessary. Owing to the large current required by the last or power valve a single stage filter for this valve will be of much the same mechanical dimensions as the multi-stage filter for the other three valves. If, however, all the valves were supplied from a common filter the mechanical dimensions of such filter and its weight and consequent cost, would be much greater than those of the two filters provided according to my invention.

Among the novel features of my invention are those particularly set forth in the appended claims. The invention itself, however, both as to its organization and its methods of operation, together with further objects and advantages thereof, will best be understood from a consideration of the following description of certain specific embodiments, taken in connection with the accompanying drawings, in which:

Figure 1 is a diagrammatic view of a receiving instrument for wireless telegraphy or telephony comprising a preferred embodiment of my invention.

Fig. 2 is a similar view of a radio receiver comprising a modified form of my invention.

Fig. 3 is a view in perspective of an iron core for a choke coil, or inductor, suitable for use in connection with the apparatus shown in Figs. 1 and 2, and

Fig. 4 is a diagrammatic view of a modified form of filter.

In all of the above referred to views like reference numerals indicate like parts where applicable throughout.

The receiver illustrated in Fig. 1 consists of a tuning arrangement 1 which is connected to an aerial and earth and to the control electrode and cathode of the first valve 2. The anode of the valve 2 is connected by a suitable coupling device 3 of known type to the control electrode of the valve 4. The anode of the valve 4 is connected by a coupling device 5 to the grid of the valve 6 and the anode of the valve 6 is connected by a coupling device 7 to the grid of the last, or power, valve 8. Of the three valves 2, 4 and 6, one constitutes what is known as a detector and the

others are voltage amplifying devices and may act at radio frequency or audio frequency according to the position in sequence of the detector valve.

Although I have described the valves 2-4 and 6 as a detector and voltage amplifying devices, my invention is not to be restricted by such a description. The first valve shown may be a radio frequency amplifying valve, as may also be the valves 4 and 6, or the latter valves may be comprised in the intermediate-frequency amplifying stages of a super-heterodyne. The said valves 2, 4 and 6 are simply shown as illustrative of any valves employed for voltage rather than for current or power amplification.

The three valves 2, 4, and 6 consume only a small amount of anode current, which may reach a total of from 3 to 6 milliamperes. The valve 8, on the other hand, which is connected to the loud speaker 9, is of the type known as a power valve, and may consume a current as great as 25 milliamperes or even greater.

The anode circuits of all of the valves are supplied from a source 10 of uni-directional current. The source 10 may be the direct-current mains, or it may be a rectifying arrangement, connected to alternating-current mains, with an appropriate reservoir condenser included in the output circuit thereof.

The negative terminal of the source 10 is connected to the common cathode conductor 11 of the amplifier. The positive terminal of the source 10 is connected to the ends of two choke coils 12 and 13. The choke coil 12 is preferably so wound with a large number of turns of very fine wire on an iron core as to have as large an inductance as may be. One end of the choke coil 12 is connected through a smoothing condenser 14 to the common cathode conductor 11 and to a common anode feed conductor 15, from which the anode circuits of the valves 2, 4 and 6 are fed. The choke coil 13 is constructed if desired on a similar iron core to that utilized for the choke coil 12, but with less turns of thicker wire, so that its current-carrying capacity is considerably greater than that of the choke coil 12, but its impedance to alternating current of any particular frequency is lower than that of the choke coil 12.

The second end of the choke coil 13 is connected through a large smoothing condenser 16 to the common cathode conductor 11 and through the loud speaker 9 to the anode of the valve 8.

The choke coil 12 and smoothing condenser 14 are designed so that the frequencies of variation of potential which may be present in the source 10 are attenuated to such a point that the potential variations which are applied to the anode of valve 2 are, when amplified by the amplifier, not made materially evident by the loud speaker 9.

The choke coil 13 and condenser 16 on the other hand are designed to attenuate the potential variations of the source 10 to a less extent, since this choke coil and condenser are connected only to the anode circuit of the last valve and potential variations therein are therefore not amplified.

The arrangement illustrated in Fig. 2 is generally similar to that illustrated in Fig. 1.

10 A separate reservoir condenser 18 is however connected across the terminals of the source 10 and a potential divider 19 is also connected across these terminals. The end of the choke coil 12 is so connected to an adjustable point

15 20 on the potential divider that the potential supplied to the amplifying and detecting valves 2, 4 and 6 may be lower than that applied to the anode of the valve 8, and may be readily adjusted independently thereof.

20 The choke coils 12 and 13 may be conveniently constructed upon a laminated core of the shape illustrated in Fig. 3. In order to facilitate the construction of these choke coils the essential dimensions are given by way

25 of example only. The air gaps 21 and 22 in the magnetic circuit may each be 1 mm. wide. The thickness of the core in a direction transverse of the laminations may be 2 cm. The width of the middle limb 24 of the core may

30 be 1.9 cm., and the width of the other limbs 25, 26, 27, 28, 29 and 30 may be 1.25 cm. For the choke coil 12 (Figs. 1 and 2) the core described may be wound with 30,000 turns of insulated copper wire 0.002" in diameter.

35 The choke coil 13 in Figs. 1 and 2 on the other hand may be wound with 4,500 turns of insulated wire 0.0068" in diameter. Thus for the choke coil 12 the magnetomotive force when 3 milliamperes are flowing through it

40 will be 90 ampere turns, while when 25 milliamperes are flowing through the choke coil 13 the magnetomotive force in this choke coil will be 112 ampere turns, and its inductance in these circumstances will be of the order of

45 25 henrys. The total weight of each of the choke coils constructed as described is about 1 lb. 10 ozs.

The smoothing condensers 14 and 16 illustrated in Fig. 1 may each be of 2 microfarads

50 capacity.

If the amplifying stages of the amplifier or receiver have very great over-all amplification it may be desirable to incorporate several stages of high attenuation in the filter which supplies the amplifying stages of the receiver with current, as shown in Fig. 4. For this purpose additional choke-coils 31 and 32 and condensers 33 and 34 are added to increase the attenuation of the filter which is connected to the amplifying valves.

It will be appreciated that the two filters may both be fed from a common rectifier in cases where the supply is taken from alternating current mains, or they each may be

65 fed from an independent rectifier. Where

direct current mains are used both filters may, of course, be connected directly to the mains or one or both may be connected to one or more potential dividers which are connected directly across the mains.

70 It will be appreciated by those skilled in the art that the above description is given by way of example only, and that many modifications may be made without departing from the scope of the invention. My invention, therefore, is not to be limited except insofar as is necessitated by the prior art and by the spirit of the appended claims.

I claim as my invention:

1. In radio apparatus, a plurality of thermionic devices relatively sensitive to anode voltage fluctuations, at least one thermionic device relatively insensitive to anode voltage fluctuations, a source of anode potential subject to fluctuation, a filter having relatively high attenuation low current capacity interposed between said source and said first mentioned devices, and a filter having relatively low attenuation and high current capacity interposed between said source and said last mentioned device.

80 2. In an amplifying system, a source of potential subject to fluctuations, a thermionic device relatively sensitive to anode potential variations connected thereto through a filter having high attenuation and low current-carrying capacity, and a second thermionic device relatively insensitive to anode potential variations connected to said source through a filter having low attenuation and high current-carrying capacity, said filtering devices having an element in common.

85 In testimony whereof, I have hereunto subscribed my name this twenty-first day of July, 1927.
